SWITCH MECHANISM

Gustave G. Hager, New York, N. Y.

Application November 16, 1940, Serial No. 365,885

4 Claims. (Cl. 200—60)

My invention relates generally to switch mechanisms, and particularly to switch mechanisms for making and breaking electrical circuits. As will be apparent from the following specification thereof, my invention is capable of many uses and applications, and it is only for purposes of convenience and not for limitation that I describe same in relation to an electric flash light. My invention is to be limited only by the scope of the annexed claims.

The main object of my invention is the provision of a switch mechanism, certain parts of which are screw-threadedly secured together, which parts are slidably laterally with respect to each other to make and break the circuit.

Another object of my invention is the provision of a switch mechanism, certain parts of which are screw threaded together, the threads being of such construction as to permit lateral sliding movement of the parts relative to each other.

A further object of my invention is the provision of a switch mechanism, the component parts of which are screw-threadedly secured together, and in which the width of each of the individual threads is but a fraction of the width of the space or distance between the threads, so as to provide room for lateral sliding movement of the screwed together parts relative to each other.

Other objects of my invention will in part be obvious, and others will be pointed out specifically in connection with the following description of an illustrative embodiment.

In the drawings annexed hereto and forming a part hereof:

The figure is a central longitudinal cross-sectional view of one form of device constructed according to and embodying my invention.

Reference numeral 10 indicates the device generally, which comprises a cylindrical casing 12 and a circular head portion 14, fitting onto the casing. One end of casing 12 is partially closed, as by means of an inwardly extending annular shoulder 16, defining a central aperture 18. The other end 20 of casing 12 is provided on its outer surface with a square male thread 22, the width of each individual thread 24 being but a fraction of the width of the inter-thread groove 26, for the purposes to be explained below.

Head portion 14 is also circular, of such diameter as to fit onto casing 12, and the leading end 28 thereof is formed with an annular, inwardly extending shoulder 30, providing a circular opening 32 through which the light from within the casing may be projected. The other end 34 of

head 14 is provided, on its inner surface, with a square thread 36, and here again the width of each individual thread 38 is a fraction of the width of the inter-thread grooves 40; the pitch and dimensions of threads 22 and 36 being the same.

The battery 60 is disposed within casing 12, and the bulb and reflector assembly are mounted within head 14. The lens 40 is first disposed of within head 14, and secured against shoulder 30 by means of split ring 42. The bulb 44 is threaded into reflector 46, and placed within head 14 against shoulder 48. A flat circular plate 50 is provided and disposed within casing 12 against shoulder 16. A circular coil spring 52 is then fitted into casing 12 against plate 50, and an elongated flat member link 54 is provided extending from spring 52 in the bottom of casing 12 to the top of casing 12 at which point it is held in position against sidewise movement within the guideway formed by a pair of walls 56, and also by a bent over tip end portion 58 thereof.

By my arrangement, the head and casing may be moved laterally with respect to each other to make and break the circuit. The circuit may be made or broken in other ways.

When the two end portions 12 and 14 are screwed together, as shown in full lines in Figure 1, the battery and reflector and link assembly 30 will all be held in their illustrated positions against dislodgment. When it is desired to complete the circuit, all the way from battery 60, through coil spring 52, link 54, reflector 48, bulb 44, back to battery 60, the head member assembly 35 is moved or shifted laterally against casing 12 into the dotted line position shown in the drawing. This sliding movement, against the tension of spring 52, brings the underside of reflector 48, of conductive material, into contact with the leading and bent-over end 58 of link 54, also of conductive material, completing the circuit. As an alternative method, plate 50 is pushed inwardly, through opening 18. This forward movement, tensioned by spring 52, will shift battery 60 and link end 58 forward until contact is made against the underside of reflector 48 completing the circuit.

The end members 12, 14 are always screw-threadedly secured together, yet are slidably or shiftable movable laterally with respect to each other, and it is the provision of my particular type and size and width of thread which permits this relative lateral movement in the making and breaking of the circuit. Casing 12 and head 14 may be formed, as by molding or other-

wise, of any suitable material, and the other parts of my device are of such simple construction as to permit of inexpensive and simple manufacture and assembly.

Having now described my invention, what I claim and desire to secure by Letters Patent is:

1. A switch mechanism for an electrical circuit comprising a pair of members screw-threadedly secured together, and means to permit relative lateral movement between said members to make and break the circuit, which means comprise a loose lateral engagement between the screw-threadedly secured together members.

2. A switch mechanism comprising a pair of members, screw thread means to secure same together, and a loose lateral fit between the screw

threads to permit shifting of said members laterally with respect to each other.

3. A switch mechanism comprising a pair of members and screw thread means on each thereof to secure same together, the width of each thread being a fraction of the width between the threads.

4. A switch mechanism comprising a pair of members, screw threads on the outside of one and screw threads on the inside of the other, said members being threadedly secured together, the width of the respective threads being but a fraction of the distance between the threads, said secured-together members being relatively shiftable laterally to make and break a circuit.

GUSTAVE G. HAGER.
